(57) **CLAIM**

The ornamental design for a knife and sheath, as shown and described.

DESCRIPTION

FIG. 1 is a front perspective view of the knife and sheath design of the present invention with the sheath in place.

FIG. 2 is a front perspective view of the knife and sheath design of the present invention with the knife removed from the sheath.

FIG. 3 is a top view of the knife and sheath design of the present invention with the sheath in place.

FIG. 4 is a top view of the knife design of the present invention with the knife removed from the sheath.

FIG. 5 is a bottom view of the knife and sheath design of the present invention with the sheath in place.

FIG. 6 is a bottom view of the knife design of the present invention with the knife removed from the sheath.

FIG. 7 is a right side view of the knife and sheath design of the present invention with the sheath in place.

FIG. 8 is a right side view of the knife design of the present invention with the knife removed from the sheath.

FIG. 9 is a left side view of the knife and sheath design of the present invention with the sheath in place.

FIG. 10 is a left side view of the knife design of the present invention with the knife removed from the sheath.

FIG. 11 is a front view of the knife and sheath design of the present invention. The circled area indicated (15) is enlarged in FIG. 15 to show detail of the design of the present invention.

FIG. 12 is a rear view of the knife and sheath design of the present invention with the sheath in place.

FIG. 13 is a front view of the knife design of the present invention with the knife removed from the sheath. The circled area indicated (16) is enlarged in FIG. 16 to show detail of the design of the present invention.

FIG. 14 is a rear view of the sheath design of the present invention.

FIG. 15 is an enlarged view of the circled area indicated (15) from FIG. 11, showing detail of the sheath design of the present invention; and,

FIG. 16 is an enlarged view of the circled area indicated (16) from FIG. 13, showing detail of the knife design of the present invention.

The portions shown by broken lines are for illustrative purposes only and form no part of the claimed design.

1 Claim, 16 Drawing Sheets
